(57) **CLAIM**

The ornamental design for a coat hanger, as shown and described.

DESCRIPTION

FIG. 1 is a top right perspective view of a coat hanger according to the present invention;

FIG. 2 is a top left perspective view of the coat hanger of FIG. 1;

FIG. 3 is a front view of the coat hanger of FIG. 1;

FIG. 4 is a rear view of the coat hanger of FIG. 1;

FIG. 5 is a left side view of the coat hanger of FIG. 1;

FIG. 6 is a right side view of the coat hanger of FIG. 1;

FIG. 7 is a top view of the coat hanger of FIG. 1;

FIG. 8 is a bottom view of the coat hanger of FIG. 1;

FIG. 9 is a top right perspective view of the coat hanger of FIG. 1 shown in a partially folded position;

FIG. 10 is a top right perspective view of the coat hanger of FIG. 1 shown in a fully folded position;

FIG. 11 is a front view of the coat hanger of FIG. 1 shown in a partially folded position; and,

FIG. 12 is a front view of the coat hanger of FIG. 1 shown in a fully folded position.

The broken lines shown form no part of the claimed design.

1 Claim, 10 Drawing Sheets
